W. E. TURNER.
AUTOMATIC OVEN HEAT REGULATOR.
APPLICATION FILED JULY 16, 1917.

1,266,886.

Patented May 21, 1918.

UNITED STATES PATENT OFFICE.

WALTER EBER TURNER, OF PIQUA, OHIO, ASSIGNOR TO THE FAVORITE STOVE & RANGE CO., OF PIQUA, OHIO.

AUTOMATIC OVEN-HEAT REGULATOR.

1,266,886.

Specification of Letters Patent. Patented May 21, 1918.

Application filed July 16, 1917. Serial No. 180,792.

To all whom it may concern:

Be it known that I, WALTER EBER TURNER, a citizen of the United States, residing at Piqua, in the county of Miami and State of Ohio, have invented certain new and useful Improvements in Automatic Oven-Heat Regulators, of which the following is a specification.

This invention relates to new and useful improvements in thermostatic devices or self-acting means affected by changes in temperature and automatically regulating the supply of fuel such as gas, either natural or artificial, to an oven or any other heating apparatus so that the heat may be controlled and maintained at any desired temperature. The invention is more particularly designed for use in connection with gas ranges or ovens in household or domestic use. The object of the invention is to provide a device of this character which is of simple construction and of maximum efficiency and wherein a range of temperature control is had. With these ends in view, certain elements are employed among which is means for determining the range of temperature control in combination with other devices which will be more fully described in the following specification.

Before describing the invention in detail reference is made to the accompanying drawings of which Figure 1 is an elevation of a well-known form of gas range having my improved thermostat or temperature-controlling device applied thereto. Fig. 2 is a somewhat enlarged perspective view of the thermostat and cooperating parts including a portion of the burner, the parts being removed from their operative position as shown in Fig. 1. Fig. 3 is a detail view of a somewhat modified form of scale indications or dial upon which the degrees in Fahrenheit are shown.

In a detailed description of the invention similar reference characters indicate corresponding parts both in the description and in the drawings.

As hereinbefore stated, the thermostat or temperature-controlling device is particularly designed for service in connection with gas ranges or ovens for household or domestic use. In the drawings I have illustrated it in connection with a gas range in the oven of which it is located in a position to control the burner thereof, or rather, the

heat generated by the oven burner. The temperature indicator is located at a convenient place. The burner may be of any of the well-known forms of gas burners. In the drawings I have illustrated a rectangular form of burner 1 with a mixer 2 into which the supply pipe or jet 3 projects, the said supply pipe or jet having an orifice which is controlled by a suitable needle valve 4. The needle valve extends through an opening in a portion of the burner to which the mixer is attached and said needle valve is connected to the lower end of a thermostatic bar 5, said bar being formed by fusing two metals together which have a different coefficient of expansion as is well-known in the construction of thermostats. The end of the thermostatic bar opposite that end which is connected to the needle valve extension, is connected to one end of a longitudinally movable pin 6. The pin 6 passes through a stationary guide or block 7 and is freely movable through the opening in said block provided therefor. The free end of the pin 6 engages the tapered side of a movable cam wedge 8 which in turn is connected with a connecting rod 9, such connection being at the upper end of the cam wedge 8. The movable cam wedge 8 is kept in contact with a guide or block 20 in which it is movable up and down. The guide or block 20 is made stationary by being screwed or otherwise fixed at a suitable point. A suitable spring 10 is employed to maintain the pin 6 in contact with the movable cam wedge 8. In the drawings I have shown such spring having one end attached to the pin 6 and the other end made fast at a convenient point, the said spring having a force sufficient to maintain such contact of the pin and thereby the cam wedge is kept in engagement with its guide. Of course, it will be understood that means may be employed for moving the pin in setting the position of the thermostat and valve, for example, a cam other than the wedge-like form as shown might be effectively employed, and any suitable form of spring may be used for exerting the necessary force upon the pin in the direction of the cam wedge 8, my purpose being to employ any device by which the thermostatic element can be moved back and forth to position the valve relative to the fuel inlet. The connecting rod 9 extending from the cam wedge 8 is in turn connected with a le-

ver 11 having a fulcrum 12 at or near its center upon which it has a reverse motion. A suitable connection is made between the lever 11 and the indicating dial 13 whereby the lever 5 may be set to the desired temperature as shown on the divisional scale of the indicator and the valve correspondingly moved. This connection with the lever may be either by means of a cam, or gearing, or 10 any other suitable connection which will enable the lever to be moved and therewith the thermostat and valve to the desired positions as indicated by the dial. In the drawings I have shown the end of the lever 11 15 as terminated in an internal rack 14 which meshes with a pinion 15 secured to the dial spindle 16 and to which spindle is also secured the dial pointer 17 which moves over the face of the dial. It will be understood 20 that the indicator dial is properly calibrated or divided to show the degrees of Fahrenheit. By turning the spindle 16 the lever 11 is set at the desired temperature and this temperature will be automatically maintained. It will be understood that in the 25 movement of the lever 11 the cam wedge 8 is correspondingly moved and the range of temperature to which the lever has been set is thereby controlled. It will be further 30 understood that as the cam wedge 8 is moved upwardly by the adjustment of the lever 11, the pin 6 and the thermostat 5 are thereby caused to move farther away from the orifice in the burner pipe 3 and thus the needle 35 valve 4 is moved out of said orifice, and therefore, before the gas can be diminished in its flow, it becomes necessary for the thermostat to move much farther thus requiring a greater temperature to enable it to do so. 40 The temperature may be maintained at a lower point by reversing the operation as above outlined or, in other words, by moving the cam wedge 8 downwardly through an elevation of the lever 11. In Fig. 3 I have 45 shown a somewhat modified form of dial or calibrated scale 19 which is in the form of a segment. In this case the end of the lever 11 nearest the indicator is provided with a pointer 18 which co-operates with the degree 50 marks in indicating the temperature.

It will be apparent that modifications may be made to a greater or less extent in details of construction without departing from the essential features of the device, among which is a cam member through the instrumentality of which the range of temperature within the oven may be varied and automatically maintained at a given point. Such modifications are contemplated within the scope of the subjoined claims. 60

Having described my invention, I claim:

1. In a device of the character specified, a fuel inlet member, a needle valve coöperating therewith adapted to control the admission of fuel to a burner, a thermostatic element connected to said valve, a supporting member for said thermostatic element, a cam adapted to vary the position of the supporting member of the thermostatic element, a lever adapted to move said cam, and a temperature indicator associated with said lever and by means of which the extent of movement of the lever is determined. 65

2. In a device of the character specified, a fuel inlet member, a needle valve coöperating therewith adapted to control the admission of fuel to a burner, a thermostatic element connected to said valve, a shiftable support for said thermostatic element, a movable wedge-like member engaging said shiftable support and adapted to change the normal position of the needle valve with reference to the fuel inlet, a spring exerting a force on said shiftable support counter to that of the wedge-like member, and means 70 80 85 for actuating said wedge-like member in opposite directions.

3. An automatic fuel regulating device comprising in combination with a valve controlling the admission of fuel to a burner, a thermostatic bar having one end directly connected to said valve, a shiftable supporting member for said thermostatic bar and to which the other end thereof is directly connected, and means including as an element 90 95 a lever for moving said supporting member in adjusting the position of the thermostatic bar relative to the valve.

In testimony whereof I affix my signature.
WALTER EBER TURNER.
